LAUNDRY ASSORTING DEVICE

Filed Oct. 13, 1930

UNITED STATES PATENT OFFICE

CHARLES F. MILLER, OF CINCINNATI, OHIO, ASSIGNOR TO THE NATIONAL MARKING MACHINE COMPANY, OF CINCINNATI, OHIO, A CORPORATION OF OHIO

LAUNDEY ASSORTING DEVICE

Application filed October 13, 1930. Serial No. 488,458.

It is the object of my invention to provide in a laundry assorting device of the type having a guide arm or accumulator for receiving a series of laundry tags or pins, all of which have the same identification mark, to identify laundry articles to which said tags or pins are attached from laundry articles having tags or pins bearing other identification marks, means for normally rejecting all laundry tags or pins other than those bearing the specific identification mark. A further object is to provide in connection with an assorting device having a tag rejector electrically operated means for causing said rejecting means to become inoperative, and means controlled by placing a proper tag in operative relation with the accumulator for causing said electrical circuit to become operative.

More specifically it is the object of my invention to provide in a laundry assorting device of the type above referred to, having a horizontally supported arm and a series of laundry tags provided with openings for receiving said arm, a pivoted gate or member designed to rest normally in a closed position for preventing tags from being placed on said arm, and latching means for retaining the said gate in a closed position, and in connection therewith improved electrically operated means for releasing said latch, said means including a normally open circuit.

A further object is to provide tags with means whereby said electrical circuit will be closed at the time the tag is placed in position to be placed on said arm, whereby the said tag will cause the gate to be released to permit the tag to be placed on the supporting arm.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a perspective view of one form of my improved laundry assorting device.

Figure 2 is a longitudinal sectional view of the gate and a portion of the mechanism for latching and unlatching the same, and show-

ing one of my improved laundry tags placed in operative position, said tag being in section.

Figure 3 is a top view of the gate and the latch mechanism for supporting the same in a closed position.

Figure 4 illustrates a laundry tag adapted to be used in connection with a laundry pin such as employed in carrying out my invention.

Figure 5 illustrates the lower end of my improved gate and the arrangement of the electric contacts designed to be used in connection with the tag as illustrated in Figure 4.

Figures 6 and 7 illustrate coacting gate members and identification tags having another arrangement of coacting contact members.

My improved device comprises a base 10 having a standard 11 to which a horizontally supported guide or arm 12 is attached. Said arm is preferably rectangular in cross section. Supported horizontally above the arm 12 is a beam 13. The outer end of said beam 13 has a pivotally mounted gate 14, the free end of which projects downwardly and terminates a slight distance above the outer end of the arm 12, in such manner that the outer end of the arm 12 will project a slight distance outwardly and beyond the lower end of said gate.

The upper end of the gate 14 has a rearwardly projecting lug 15 designed to rest on the upper edge of the beam 13 when the gate is in its normal vertical position. The upper face of the beam 13 is provided with a slidably mounted latch bar 16 having at its forward end an upwardly and outwardly inclined portion 17 terminating in a horizontal portion 18 designed to rest normally above the lug 15.

The latch portion 18 prevents the lower end of the gate 14 from being swung inwardly while the lug 15 prevents the lower end of the gate from being swung outwardly. Said gate 14 is mounted on a pivot member 19 fixed in said beam, and said pivot has provided at one end a spring 20 for returning the gate to its vertical and normal position and for

yieldably retaining the gate in said position.

Supported on the upper end of the standard 11 and on the rear end of the beam 13 is an electric solenoid 21 having a slidably mounted core 22. Said core is connected to the rear end of the slide bar 16. A spring 23 is provided for returning the slide bar 16 to its forward position of movement and for normally holding the same in said forward position.

One side of the gate 14 is provided with a cam plate 24, one edge of which is concentric to the center of the pin 19. The top edge 25 of the plate is designed to be engaged by a roller 26 carried by one edge of the slide member 16, when the slide member is in its closed position of movement. Said roller is designed to be moved rearwardly and to engage the curved edge of said plate 24 at the time the lower end of the gate 14 is swung inwardly, and to prevent the latch 18 from moving into latching position until after the gate has moved to its normal vertical position of movement, for purposes hereinafter made clear. The lower end of the gate 14 is provided with a pair of contact members 27, one of which is connected to a conductor 28 and the other to a conductor 29. The conductor 28 includes the solenoid 21, said wires being adapted to be connected to any suitable supply of electric current, whereby closing the contacts 27 will cause the conductors 28 and 29 to be energized and the core 22 drawn inwardly into the solenoid, causing the latch 16 to be moved inwardly against the tension of the spring 23 and the latch 18 to be released from the lug 15, permitting the gate 14 to be swung inwardly.

The guide 12 is designed to support a series of laundry tags 30, each of which is provided with a rectangular opening 31 for receiving said guide. Each of the tags 30 is preferably provided with a pin 32 by means of which the tag may be secured to the laundry article. Each of the tags 30 is provided with a suitable identification mark 33 in the usual manner.

In actual operation a series of tags is provided with the same identification mark, all of the tags of a given series having the same identification mark being designed to be carried by the guide 12, while a second series of tags is provided with a different identification mark 34. Said second series is adapted to be supported by a second guide, so that laundry articles carried by the first series of tags may be separated and supported separately from the laundry articles carried by the second series. Each of the assorting devices is provided with an identification mark 35 corresponding to the series of tags designed to be collected thereby.

Each of the tags 30 is provided with a pair of embossed contact portions 36 arranged in

such manner as to make connection with the contact members 27 in such a manner that when the tag 30 is placed on the outer end of the arm 12, said members 27 and 36 will engage each other and close the circuit through the conductors 28 and 29. 70

The tag 30 is formed preferably of metal, and therefore a conductor of electricity, and provides means for closing said circuit when the tag is placed in position. As soon as the circuit is closed, the latch 18 is released in the manner before described. 75

The tag 30 is then pressed inwardly, causing the lower end of the gate 14 to be swung inwardly, permitting the tag to be placed in position on the guide 12. At the time the latch 18 is moved inwardly, the roller 26 will engage the curved edge of the plate 24, and thus provide means for retaining the latch 18 at its inner limit of movement until the gate 14 has been returned to its vertical position. 85

It will readily be seen that as soon as the lower end of the gate 14 is moved inwardly, a slight distance, contact between the portions 27 and 36 may be broken before the tag has been moved to position from beneath the lower end of the member 14, which will permit the latch 18 to move to a latching position before the gate 14 returns to its normal position. This is overcome by the roller 26 and the plate 24. 90

In Figures 6 and 7 I have illustrated another arrangement of the contacts 27 and 36, whereby if the tag B is placed on the guide 12, which is normally designed to support the tag A, then the contact members 36 of the tag B will not register with the contact members 27 of the gate A, and consequently the gate would not be unlatched, and it would be impossible for the operator to place the tag B on the guide intended to carry the A series of tags. 95

While in the drawing I have illustrated the tags 30 as being connected to laundry pins, it will readily be seen that other means of connecting the tag with the garment might be provided without departing from the spirit of my invention. For instance, the tag 30 might be sewed to one edge of the garment, in which case the function of the tags and the assorting device would be exactly the same. 110

Thus it will be seen that I have provided in a laundry assorting mechanism of that type designed to support a given series of identification tags improved means whereby all of the tags except those of the proper series will be automatically rejected, and in connection therewith improved electrically operated means whereby the proper tag may be permitted to be placed in its operative position, thereby providing a simple and inexpensive means to assist in the assorting of laundry articles, whereby errors in placing the laun- 120

dry tags in their assorting devices will be eliminated.

I claim as my invention:

1. The combination of a tag accumulator 5 having a tag supporting arm adapted to support a series of tags each having the same identification mark, a tag rejector, electrically operated means for rendering said rejector inoperative, said electrically operated means 10 including a normally open circuit, and means carried by each of said tags for closing said circuit when a tag carrying said identification mark is placed in operative relation with said arm, whereby all tags having said 15 identification mark will be accepted.
2. In combination, a tag accumulator having a tag supporting arm adapted to carry a series of tags each having the same identification mark, a tag rejector, a normally open 20 electric circuit, means carried by each of the tags of said series for closing said circuit when one of the tags is placed in predetermined operative relation to said supporting arm, and means actuated by the closing of 25 said electric circuit for rendering said rejector inoperative and permitting any tags of said series to be accepted.

3. In combination, a tag accumulator for supporting a series of tags each having the 30 same identification mark, an electric circuit, a tag rejector, means actuated by said electric circuit to permit tags to be accepted when the circuit is placed in operative condition, and means carried by each tag of said series 35 of tags for causing said electric circuit to be placed in operative condition when said tag is placed in a predetermined position relative to said accumulator.

4. In a laundry assorting device, the combination of a support, a guide arm adapted 40 to support a series of tags each having the same identification mark and an opening for receiving said arm, a beam supported above said guide, a gate movably mounted on the 45 outer end of said beam and designed to rest normally in a predetermined position with its free end adjacent to said guide, a latch device for locking said gate in said predetermined position, and electrically operated 50 means for releasing said latch, said electrically operated means including conductor wires, each having a terminal carried by the free end of said gate.

5. In a device of the class described, the combination of a support, a guide arm adapted 55 to support a series of tags each having the same identification mark, a tag rejector, electrically operated means for rendering said rejector inoperative, said electrically operated 60 means including a normally open circuit, and means adapted to co-operate with any tag of said series of tags to close said circuit when the tag is supported in a predetermined position relative to said arm.

6. In a device of the class described, the

combination of a support, means adapted to support a series of tags each having the same identification mark, a movable tag rejector for preventing tags from being placed on said tag supporting means, means for locking said rejector in operative position, and electrically operated means for releasing said locking means, said electrically operated means including means controlled by any one of said series of tags to release said locking means when said tag is placed in a predetermined position relative to said arm.

7. The combination of a tag support adapted to carry a series of tags each having the same identification mark, a tag rejector, electrically operated means including an electric circuit for causing said rejector to become inoperative, and means actuated by placing one of said tags in a predetermined position relative to said support for placing said electric circuit in condition to cause said electrically operated means to operate.
